ATTORNEYS

UNITED STATES PATENT OFFICE.

SHERMAN T. ALLEN, OF BEVERLY HILLS, CALIFORNIA.

DESIGN FOR A VENDING-MACHINE CASING.

Application filed June 12, 1929. Serial No. 31,651. Term of patent 3½ years.

To all whom it may concern:

Be it known that I, SHERMAN T. ALLEN, a citizen of the United States, residing at Beverly Hills, in the county of Los Angeles, State of California, have invented a new, original, and ornamental Design for Vending-Machine Casings, of which the following is a specification, reference being had to the accompanying drawing, forming part thereof.

The figure is a perspective view of a vending machine casing showing my new design.

I claim:

The ornamental design for a vending machine casing as shown.

SHERMAN T. ALLEN.
